UNITED STATES PATENT OFFICE.

EDWARD EVERETT NELSON, OF FILLMORE, ILLINOIS, ASSIGNOR OF ONE-HALF TO GEORGE W. PERKINS AND NED B. ALLEN, OF SAME PLACE.

COMBINED DOOR LATCH AND LOCK.

SPECIFICATION forming part of Letters Patent No. 634,365, dated October 3, 1899.

Application filed May 27, 1899. Serial No. 718,551. (No model.)

To all whom it may concern:

Be it known that I, EDWARD EVERETT NELSON, of Fillmore, in the county of Montgomery and State of Illinois, have invented new and useful Improvements in a Combined Door Latch and Lock, of which the following is a full, clear, and exact description.

The object of this invention is to provide a novel, simple, and inexpensive combined door latch and lock which is devoid of springs, is reliable in service, and which affords means for the locking of both the latch-bolt and lock-bolt at the same time, thus affording double security in a very effective manner.

The invention consists in the novel construction and combination of parts, as is hereinafter described, and defined in the claims.

Reference is to be had to the accompanying drawings, forming a part of this specification, in which similar characters of reference indicate corresponding parts in all the figures.

Figure 1 is a side view of the lock-case with a side plate thereof removed, exposing the working parts, which are adjusted to lock the latch-bolt against retraction and hold the locking-bolt proper in unlocked condition. Fig. 2 is a view of the lock-case similar to that shown in Fig. 1, the details of the latch and lock being shown adjusted to release the latch-bolt, which is represented in retracted adjustment. Fig. 3 is a side view of the lock-case with one side removed, exposing the working parts of the latch and lock, that are both shown in locked condition. Fig. 4 is a transverse sectional view substantially on the angular line 4-4 in Fig. 1. Fig. 5 is a longitudinal sectional view of the lock substantially on the line 5-5 in Fig. 3. Fig. 6 is a perspective view of the locking slide-bolt, and Fig. 7 is a perspective view of a novel tumbler-bar that is a detail of the lock.

In the drawings that represent an embodiment of my invention, 8 indicates the case wherein are held the operative details of the lock and latch in proper relative positions. The case 8 is rectangular and recessed, as usual in box form, to adapt it to contain the working parts, to be presently described, and on the open side of the case is held by screws inserted at the corners the cover-plate 8^a,

that serves to complete said case when it is secured in place.

The latch-bolt 9 is held to slide longitudinally in the case 8 through an opening in one end wall of the latter by its loose engagement between the spaced studs a, that project from the fixed side wall of the case near the rear end of the latch-bolt, the latching end of said latch-bolt being loosely retained in place by contact with the sides of the aperture in the end wall of the case.

Above the slidable latch-bolt 9 a two-part pusher-bar is supported in the case 8 and, as shown, comprises a T-block 10 and a rocking bar 11, the T-block consisting of three members b b' b², which are arranged substantially in T form. The member b, which is uppermost, is pivoted upon the fixed side wall of the case 8 by a pivot bolt or stud c, and below this member in the same upright plane the member b' is downwardly projected, while the remaining member b² is laterally extended from the members b b' intermediate of their ends and away from the end wall of the case, through which the latch-bolt 9 is adapted to slide.

The depending limb b' of the T-block 10 is slotted upwardly from its free lower edge at right angles, and laterally-projecting pins d on the sides of the latch-bolt 9 have loose engagement with said slot, the latch-bolt being loosely embraced by the two spaced members formed by another slot in the limb b'. (See dotted lines in Figs. 1, 2, and 3.)

The rocking bar 11 is slotted vertically and longitudinally in the end portion that is to connect with the limb b² of the T-block 10, and said limb b² is preferably reduced in thickness where it is inserted within the slot in the bar 11. A transverse slot e is also formed in the end portion of the rocking bar 11, and a pin e', which projects from the part of the limb b² that occupies the vertical slot in the bar 11 passes loosely through the slot e, which affords a rockable and slidable joint between the T-block 10 and the end of the rocking bar 11.

The end of the rocking bar 11 opposite from its slotted extremity is pivoted upon the fixed wall of the case 8, as at f, and intermediate of said ends on the top of the rocking

bar a gravity-block g is formed or secured. On the T-block 10 at the upper corner between the limbs b and b^2 a weight-block h is located, which adds to the heft of the T-block, 5 and serves to quickly and reliably depress the limb b^2 of the T-block when said limb is elevated above a horizontal position.

The usual knob-shank or spindle 12 is provided for the actuation of the latch-bolt 9 through the medium of the parts 10 11, and said shank extends through the case 8 at each side, as indicated in Fig. 4, for the reception of knobs or equivalent means for turning the shank. A trip-finger 13 is secured on the shank 12, and the latter being positioned below the rocking bar 11 permits the end of the trip-finger to engage with the lower edge of said bar and raise it, when the shank is rotatably moved in the direction of 20 the arrow w .

The weight of the T-block 10 and rocking bar 11, together with the gravity-blocks g and h thereon, normally depresses the bar 11 until it rests upon the hub of the trip-finger 13, 25 and thus depresses the toe of the trip-finger, as shown in Figs. 1 and 3, the bar 11 being supported substantially horizontal.

When the parts 10 11 are in normal adjustment as just described, the sloped end of the 30 latch-bolt 9 is fully projected out of the case 8 to have latched engagement with an ordinary hasp-plate, (not shown,) and thus retain closed the door on which the lock is secured.

When the shank or spindle 12 is rocked in 35 the direction of the arrow w , the upward inclination of the rocking bar 11 thus effected will correspondingly lift the limb b^2 of the T-block 10, as shown in Fig. 2, which will rock the limb b^2 rearwardly and pull the latch-bolt 40 9 inwardly, as clearly represented in said figure.

The rocking bolt 14 is horizontally supported free to slide endwise through a suitable orifice in the end wall of the case 8 by 45 the projections i , which are formed on the side wall of the case.

The bolt 14 is elongated and rectangular in cross-section and its body is vertically and longitudinally slotted from the inner end sufficiently to receive the tumbler-bar 15, designed to move freely in said slot. The tumbler-bar 15 is pivoted at one end upon the fixed side wall of the case 8 and upon the cover 8^a, and at the opposite end, which is 55 located near the forward termination of the slot in the bolt 14, a cross-pin m is projected from said tumbler-bar, which pin may engage in either of two spaced notches n n' , formed in the upper edge of the locking-bolt.

60 A weight-block 15^a is formed or secured upon the upper edge of the tumbler-bar 15 above the cross-pin m and serves to enforce the depression of the tumbler-bar at its free end and cause the cross-pin m to enter either 65 notch n n' above which it may be located.

A scallop o is cut in the lower edges of the parallel members of the locking-bolt, so as to

expose the body of the tumbler-bar 15 at the apex of said scallop, and keyholes p , formed oppositely in the side walls of the case 8 near 70 the scallop o , permit the insertion of a key 16, (shown by dotted lines in Figs. 1, 2, and 3,) so that a rocking movement of said key will cause the bit of the key to contact with the tumbler-bar and raise it a limited degree. 75

The notches n n' are so relatively located with regard to the cross-pin m and outer end of the locking-bolt 14 that said pin will fall into the outermost notch n when the key 16 has been manipulated, so as to lift the tumbler-bar 15 and at the same time draw the bolt 14 into unlocked adjustment, as represented in Fig. 2, the direction of rotatable movement of the key in this case being indicated by the arrow x in Fig. 3. 80

If the key 16 is moved in the direction of the arrow x' in Figs. 1 and 2, the tumbler-bar 15 will be rocked upwardly and thus remove the cross-pin m from the notch n , and immediately after this elevation of the tumbler-bar 90 the bit of the key will engage with the bolt 14 and push it outwardly, the extent of such sliding movement being just sufficient to release the key from the locking-bolt when the pin m is directly above the notch n' , into 95 which said pin now drops and thus locks the bolt 14 against retraction until a proper key is employed for the elevation of the tumbler-bar 15 and sliding movement of the locking-bolt, as before explained. 100

Between the latch-bolt 9 and the locking-bolt 14 a shackle-bar 17 is held to slide longitudinally, said bar being designed to simultaneously lock the latch-bolt against retraction and also lock the bolt 14 when it is outwardly projected at the same time the latch-bolt is locked. The shackle-bar 17 is of a length sufficient to permit one end to project a short distance through an aperture in the end wall of the case 8 opposite the end wall 110 through which the bolts 9 and 14 extend, while the opposite end of the shackle-bar is supported to slide adjacent to the bolts it is to hold against retraction, as will now be explained. 115

The inner extremity of the shackle-bar is bent downwardly to form a toe q , and near this toe a slot r is formed longitudinally in the body of the bar and transversely thereof. A stud s projects from the fixed side wall of 120 the case 8 into the slot r and serves to support the inner end portion of the shackle-bar, so that it may be moved endwise, the position of the stud adapting it to maintain the shackle-bar horizontal when in normal adjustment. 125

In the lower edge of the shackle-bar, near the end which projects through the end wall of the case 8, two spaced notches u u' are formed, which are designed to separately receive the lower defining edge of the aperture in the end wall of the case 8 through which the shackle-bar extends. 130

The face of the depending toe q of the

shackle-bar 17 is nearly in the same horizontal plane with the upper surface of the weight-block 15^a, so that an adjustment of the shackle-bar toward the weight-block or in the direction of the arrow *z* in Fig. 2 will locate the toe *q* directly over the weight-block, and when such an adjustment is effected the notch *u'*, that is outermost, will receive the edge of the case 8, as before mentioned, which engagement will obviously retain the shackle-bar against longitudinal movement.

It will be seen that the location of the toe *q* over the weight-block 15^a will prevent the tumbler-bar 15 from receiving upward rocking movement to release the locking-bolt 14, so that it will be impossible to retract the bolt 14 or project it outwardly by any instrument from either side of the lock until the toe *q* of the shackle-bar is removed from over the weight-block.

On the upper edge of the shackle-bar 17, at a suitable distance from the depending toe *q*, an abutment-flange *v* is formed, which extends upwardly at the rear of the latch-bolt 9 and may contact therewith.

The notches *u u'* are so spaced apart and the abutment-flange *v* so relatively positioned that when the shackle-bar 17 is adjusted by sliding it in direction of the arrow *y* to engage the innermost notch *u* with the edge of the case 8 the abutment-flange *v* will allow the latch-bolt 9 to be freely operated for its release from a hasp-plate or other keeper. (Not shown.)

In case it is desired to double lock the door having the improved lock on it, the bolt 14 is first thrown outward to engage with a hasp-plate or other keeper by the use of the key 16, and then the shackle-bar 17 is lifted at its rear end and shifted inwardly in the direction of the arrow *z*, so as to interlock the notch *u'* with the edge of the case-wall, which adjustment will secure the latch-bolt and locking-bolt in projected condition and prevent the release of either bolt until the shackle-bar is moved to effect such a release.

The shackle-bar 17 may have a weight-block 17^a formed or secured on its upper edge near the notch *u*, and if employed will aid in depression of the bar, so as to cause an engagement of either notch *u u'* with the edge of the case-wall, as occasion may require.

It will be noticed that all working parts of the combined latch and lock are very simple and cheap in production and not liable to become inoperative from ordinary wear.

It is a feature of advantage that the operative details of the improved latch and lock are actuated in part by gravity, dispensing with springs, which increases durability and renders the device very reliable in service.

Having thus described my invention, I

claim as new and desire to secure by Letters Patent—

1. The combination, with a case, of a slide-bolt, a slideable locking-bolt, and a shackle-bar having two lateral projections and slideably disposed between and parallel with said bolts, said shackle-bar being adapted by adjustment to engage the lateral projections thereon with the latch-bolt and locking-bolt, thereby securing them against retraction. 65

2. The combination, with a case, of a latch-bolt slideable longitudinally thereon, and means to slide said bolt from without the case, 75 of a locking-bolt operative with a key, and a longitudinally-adjustable shackle-bar, slideable between the latch-bolt and locking-bolt, said bar having spaced notches at its rear end to engage with the wall of the case, and lateral projections above and below thereon, respectively adapted to impinge upon the inner end of the slide-bolt and upper side of the locking-bolt, whereby to lock said bolts projected from the case. 80

3. The combination with a case, and a longitudinally-slideable latch-bolt therein, of a two-part pusher-bar comprising a weighty T-block loosely engaging the latch-bolt for its sliding movement, and a rocking bar pivoted 90 by one end to the case and jointed upon the T-block, to receive upward rocking movement, and means to rock the bar and T-block for the retraction of the latch-bolt.

4. In a device of the character described, 95 the combination with the two-part pusher-bar comprising a three-limbed T-block, pivoted to the lock-case at the upper end of the T-block, and a rocking bar pivoted by one end on the lock-case, the other end of said bar 100 having a rocking and sliding connection with a lateral member of the T-block, a slideable latch-bolt, a loose connection between the depending member of the T-block and the slide-bolt, and means to flex the two-part pusher-bar near its joint, for the actuation of the slide-bolt. 105

5. In a device of the character described, the combination with a case, and a latch-bolt and a locking-bolt, both slideable in the case, 110 of a shackle-bar held to slide in the case between the latch-bolt and locking-bolt, projections on said shackle-bar adapted to hold the said bolts against retraction, said bar having spaced notches near one projecting end 115 thereof, which by separate engagement with a part of the case are adapted to hold the shackle-bar in engagement with the latch-bolt and locking-bolt, or retracted therefrom.

EDWARD EVERETT NELSON.
